UNITED STATES PATENT OFFICE.

TOLBERT F. CHEEK, OF LYNDHURST, NEW JERSEY, ASSIGNOR TO PHIL-HAR-CHEE PIANO PLAYER CORPORATION, OF NEW YORK, N. Y., A CORPORATION OF NEW YORK.

PRESSURE-CONTROLLED PUMP FOR MUSICAL INSTRUMENTS.

1,303,029.

Specification of Letters Patent.

Patented May 6, 1919.

Application filed September 15, 1916. Serial No. 120,304.

To all whom it may concern:

Be it known that I, TOLBERT F. CHEEK, a citizen of the United States, and a resident of Lyndhurst, Hudson county, State of New Jersey, have invented certain new and useful Improvements in Pressure - Controlled Pumps for Musical Instruments, of which the following is a specification.

My invention relates to pneumatic players for musical instruments and has for its object chiefly to provide a device for maintaining a constant pressure in the wind chest under variable amounts of opening at the tracker board and thus effecting an automatic control of the pressure, and another feature of my invention consists of a novel arrangement of parts for the compact and efficient construction of a pump for operating pneumatic devices. Other features of my invention will appear from the detailed description hereinafter given, and the scope of my invention will be indicated in the appended claims.

Reference is to be had to the accompanying drawings in which Figure 1 is a diagrammatic elevation of a portion of a pneumatic player for musical instruments embodying my improvements. Fig. 2 shows, upon an enlarged scale, an outside view of the controlling device proper. Fig. 3 illustrates the said controlling device in vertical section. Fig. 4 is a vertical section of my improved pump taken on line 4—4 of Fig. 5. Fig. 5 is a rear view of said pump with the back thereof removed. Fig. 6 is a partial vertical section on line 6—6 of Fig. 5. Fig. 7 is a front view of the pump. Fig. 8 is a horizontal section on line 8—8 of Fig. 4. Fig. 9 is a horizontal section of the controlling device on line 9—9 of Fig. 2. Fig. 10 is a vertical section of said device on line 10—10 of Fig. 2 and Fig. 11 is a detail sectional view of a portion of the wind chest and its connections.

In Fig. 1, I have indicated at 20 the customary tracker over which moves the perforated music sheet 21 and from which air conduits 22 extend to the action chest 23 controlling the motor pneumatics 24 in any well known or approved manner, said chest being connected by a trunk 25 with a wind chest 26 having receivers 27. These parts may be of any approved construction and have been shown only for the sake of com-

pleteness. It will be understood that I may provide the usual pedal mechanism for creating and maintaining a vacuum in the wind chest 26, but the presence of such pedal mechanism is not essential to my invention, that is to say, the device may be operated without any pedal mechanism.

The wind chest has an opening 26' (see Fig. 11) controlled by an outwardly opening flap valve 26'' and when said valve is opened the wind chest 26 communicates with a small chamber 28 from which pipes or conduits 29 and 30 lead to the pump and to the automatic controlling device respectively. The pump is provided with a back 31 adjacent to which there are two chambers 32 and 33, extending side by side from top to bottom and separated by a partition 34 which is interrupted at one point 34' to form a seat for a valve 35 located in the chamber 32 and opening toward said chamber. A spring 36 tends to close the valve 35 and thus to disconnect the compartment 32 from the compartment 33. The latter compartment is in permanent communication with the pipe 29 and also has connections 33' at top and bottom communicating with passages 37 in stationary boards or members 37. From each of the passages 37', ports 37'' controlled by flap valves 38 (provided with springs 39 of usual character) lead to the interior of bellows 40, the movable end members of which, 40', are provided with ports 40'' adapted to open to the outside air when the outwardly opening flap valves 41 (provided with springs 41') are unseated. There are four movable bellows members 40' arranged in pairs on opposite sides of each of the stationary members 37 and the two members 40' of a pair are connected by links 42, the ends of which are pivoted to the respective boards or members 40'. The two innermost movable members 40' are connected pivotally with rods 43, the other ends of which are pivoted to cranks 44 and 44' secured to the drive shaft 44''. Preferably the two cranks 44 and 44' are set at 90° from each other. The shaft 44'' is driven in any suitable manner as by means of a belt applied to the pulley 45 and generally the motive power is supplied by an electric motor. In the neighborhood of the horizontal plane containing the channel 37' each of the stationary members 37 is provided with two

channels 46 preferably superimposed as indicated in Figs. 5 and 6, which channels extend to the interior of the bellows 40, where their orifices are covered by strips 47 of felt 5 or other material sufficiently porous to allow air to be drawn through. The purpose of these cover strips is to avoid noise which might result from the suction. The ends of the channels 46 adjacent to the chamber 10 or compartment 32 are normally closed by flap valves 48, pressed toward said channels by springs 49.

The controlling device, shown particularly in Figs. 1, 2, 3, 9 and 10, comprises 15 a stationary casing 50, the chamber 51 of which is permanently in communication with the pipe 30 mentioned above. From said chamber a channel 51' leads to the interior of a bellows 52 which a spring 53 tends to keep in the open or expanded position. The communication between the channel 51' and the bellows 52 is preferably made through a perforation in a disk 52' secured at the bellows end of said channel. 20 The movable member 52'' of said bellows is provided with an opening 53' adapted to place the interior of the bellows in communication with the outside air when the valve 54 is open. This valve is provided with a projecting spring member 55 for a purpose to be stated hereinafter. The chamber 51 is provided with an upper valve seat 56 on which is adapted to rest the vertically movable piston valve 57. In the position illustrated by Figs. 3 and 10 said piston valve is down and opens a communication between a port 50' leading to the outside air and a channel 50'' leading to the interior of a bellows 58. The movable member 58' of this 25 bellows is connected with a rod 59 provided with a knob 60 adapted to engage the spring 55 mentioned above. At the bottom of the chamber 51 is a diaphragm 61 normally out of engagement with a knob 57' provided at the lower end of the rod to which the movable piston valve 57 is secured. Under this 30 diaphragm there is a small chamber 62 connected by a bleeding channel 62' with the main chamber 51 so as to equalize the pressure on both sides of the diaphragm. From the lower chamber 62 a duct 63 leads to a port 63' which in the position shown in Fig. 2, is closed by a valve 64 pivoted at 64'. The movable member 52'' of the bellows 52 is 35 connected with the valve 64 by a rod 65 which slides in a suitable guide 66 on said movable member and is provided with an adjustable knob 65' adapted to be engaged by said guide when the bellows 52 is collapsed and is also provided with another adjustable knob 65'' adapted to be engaged by the guide 66 during the expanding movement of the bellows 52.

With the movable member 58' of the bellows 58 is connected, a link 67 Fig. 1, ex-

tending to a lever 68 fulcrumed at 68', the other arm of said lever being connected with a rod 69, the end of which is secured to the valve 35.

In some cases I may employ certain additional parts indicated in Figs. 1, 2 and 3, said parts comprising an additional channel 70 leading from the lower chamber 62 and connected with a pipe 71, the upper end of which is normally closed by a valve 72 within easy reach of the operator and by swinging said valve laterally on its pivot 72', the outside air may be admitted to the pipe 71 and to the lower chamber 62 for a purpose to be stated hereinafter.

Let us assume that the pump shown in Figs. 4-8 (inclusive) is relied upon as the sole means of creating a vacuum in wind chest 26, that is to say, there are no bellows operated by pedals. The shaft 44'' being 75 rotated, say, by an electric motor, the movable bellows members 40' will be swung up and down on their pivots or hinges, the valves 38 opening into the bellows every time said movable members move away from the stationary members 37 while the valves 41 open every time the movable members move toward the respective stationary members 37. The operation of the bellows therefore will withdraw air from chamber 28 by 80 exhaust or suction through the channels 37', ports 33' to chamber or compartment 33 and the pipe 29, the suction within the chamber 28 causing the valve 26'' to open so that the proper degree of vacuum is produced in the wind chest 26. The valve 35 is closed as shown in Fig. 5. The vacuum existing in the wind chest 26 will cause a similar vacuum in the action chest 23 so as to actuate the motor pneumatics 24 in the usual 85 manner whenever a perforation of the music sheet 21 registers with a perforation of the tracker 20. The vacuum will also be communicated through the pipe 30 to the chamber 51 of the controlling device. When a great many perforations of the music sheet register with the tracker bar at the same 90 time or in quick succession, a comparatively large amount of air will be drawn in through the tracker bar and the vacuum in the wind chest will be reduced correspondingly, but the pump is of sufficient capacity to keep the vacuum of proper strength so as to play in the desired manner. The spring 53 is of such power as to keep the bellows 52 expanded under the suction conditions existing at the time the instrument is playing loud owing to the fact that a large number of perforations in the tracker 20 are open at the same time. If, however, only a few 95 notes should be played at one time, the pump, which operates at a practically uniform speed, (and therefore constant capacity or duty per unit of time) will draw the air in such a manner as to produce a 100

vacuum of higher degree in the wind chest and in the chamber 51 connected thereto and this vacuum will become so strong as to overcome the resistance of the spring 53, 5 causing the bellows 52 to collapse. As this movement occurs the guide 66 will come in contact with the knob 65' and will swing the valve 64 on its pivot 64' so that finally the port 63' will be opened to the atmosphere. 10 Whenever atmospheric pressure is thus admitted to the chamber 62 the vacuum existing in the chamber 51 will cause the diaphragm 61 to move upwardly thus lifting the lower member of the piston valve 57 15 from its seat 56 and bringing the upper member of the piston valve against the opening 50' so as to close the latter. The interior of the bellows 58 is then in communication with the chamber 51 through the passage 20 50" and the suction of the pump will cause the bellows 58 to collapse. During this movement the knob 60 will strike against the spring 55 and cause the valve 54 to open, thus admitting the surrounding air to the 25 interior of the bellows 52. The piston valve 57 will then drop to its former position shown in Fig. 3 and the bellows 58 will resume its expanded condition, it being understood that said bellows is preferably provided with a spring 58" similar to the 30 spring 53. The spring 36 also tends to expand the bellows 58, through the connection 69, 68, 67. Whenever the bellows 58 is collapsed, the pull on the rod 67 will result in 35 a push on the rod 69 and open the valve 35. When this occurs the vacuum produced by the suction of the pump in the chamber 33 will also be exerted in the chamber 32 and a portion of the air will be circulated 40 through or within the pump itself, that is to say, the air passing from the chamber 33 through the ports 33' and into the interior of the bellows 40 will partly return from said bellows through the channels 46 and 45 the valve 48 to the compartment 32 from which it passes through the opening 34' into the compartment 33 and back to the suction ports 33' of the pump. Thus a portion of the air set in motion by this pump will 50 simply circulate within the pump and the degree of vacuum produced by the pump under these circumstances in the wind chest 26 will be much less than it is when the entire capacity of the pump is employed to 55 suck air out of the wind chest. I therefore obtain automatically a varying volume of sound in the playing of the music, each note being struck with practically the same force, and the instrument therefore playing 60 with a great volume of sound when a comparatively large number of notes occur at the same time or in quick succession, whereas a softer playing that is to say, a smaller volume of sound is obtained automatically 65 whenever there are only a few notes at the

same time or in quick succession. It may be desirable for the performer to secure soft playing at will and not only automatically as described above. When this result is desired, the performer will swing the valve 72 70 so as to admit atmospheric air to the pipe 71, the duct 70 and the chamber 62, this having of course the same result as has been described above in connection with the opening of the valve 64. It will be understood 75 that the latter valve is brought back to its normal position by the action of the guide 66 on the knob 65" near the end of the rod 65. The valve 72 will enable the performer to vary the expression, or loudness of play- 80 ing, irrespective of the number of notes which are struck at the same time.

While I have described the pump driven by an electric motor or the like, as the sole means of producing a vacuum in the wind 85 chest 26, it will be understood that if desired the usual pedal operated bellows might be employed for this purpose, the pump above described not being operated in that case. This is the reason I have shown the 90 valve 26" which will close automatically whenever the vacuum in the wind chest 26 is produced by pedal operated bellows and the pump above described is thrown out of 95 operation.

I claim:

1. In an automatic player for musical instruments the combination of a wind chest, a pump connected with said wind chest and provided with a by-pass for allowing a portion of the air set in motion by the pump to circulate within the pump, a valve for closing said by-pass, an automatic pressure controlling device having a chamber connected with said wind chest permanently, another chamber adapted for connection with the surrounding air, a valve controlling the connection of said second-named chamber with the surrounding air, means responsive to a change of pressure in the first-named chamber for operating the second-named valve, a movable wall separating said two chambers, pneumatically-operated means for moving the first-named valve, and a third valve operated by the movement of said wall for 100 either connecting said pneumatically-operated means with the first-named chamber of the pressure controlling device or disconnecting it therefrom. 110

2. In an automatic player for musical instruments the combination of a wind chest, a pump connected with said wind chest and provided with a by-pass for allowing a portion of the air set in motion by the pump to circulate within the pump, a valve for closing said by-pass, an automatic pressure controlling device having a chamber connected with said wind chest permanently, another chamber adapted for connection with the surrounding air, a valve controlling 120 125 130

- the connection of said second-named chamber with the surrounding air, means responsive to a change of pressure in the first-named chamber for operating the second-named valve, a movable wall separating said two chambers, pneumatically-operated means for moving the first-named valve, and a third valve operated by the movement of said wall for connecting said pneumatically-operated means either with the surrounding air or with the first-named chamber of the pressure controlling device.

3. In an automatic player for musical instruments the combination of a wind chest, a pump connected with said wind chest and provided with a by-pass for allowing a portion of the air set in motion by the pump to circulate within the pump, a valve for closing said by-pass, an automatic pressure controlling device having a chamber connected with said wind chest permanently, another chamber adapted for connection with the surrounding air, a valve controlling the connection of said second-named chamber with the surrounding air, a normally expanded bellows communicating permanently with the first-named chamber of the pressure controlling device, means operated by said bellows for controlling the second-named valve, a movable wall separating the two chambers of the pressure controlling device, a second bellows, means connected with said second bellows for operating the first-named valve, and a third valve, operated by the said movable wall for connecting said second bellows either with the surrounding air or with the first-named chamber of the pressure device.

4. In an automatic player for musical instruments the combination of a wind chest, a pump connected with said wind chest and provided with a by-pass for allowing a portion of the air set in motion by the pump to circulate within the pump, a valve for closing said by-pass, an automatic pressure device having a chamber connected with said wind chest permanently, another chamber adapted for connection with the surrounding air, a valve controlling the connection of said second-named chamber with the surrounding air, a normally expanded bellows communicating permanently with the first-named chamber of the pressure device, means operated by said bellows for controlling the second-named valve, a movable wall separating the two chambers of the pressure device, a second bellows, means connected with said second bellows for operating the first-named valve, a third valve operated by said movable wall for either connecting said second bellows with the first-named chamber of the pressure device or disconnecting it therefrom, and means operated by said pneumatically-operated means at the time the latter opens the first-named valve for causing said pressure-responsive means to close the second-named valve.

5. In an automatic player for musical instruments, the combination of a wind chest, a pump connected with said wind chest and provided with a by-pass for allowing a portion of the air set in motion by the pump to circulate within the pump, a valve for closing said by-pass, an automatic pressure device having a chamber connected with said wind chest permanently, another chamber adapted for connection with the surrounding air, a valve controlling the connection of said second-named chamber with the surrounding air, a normally expanded bellows communicating permanently with the first-named chamber of the pressure device, means operated by said bellows for controlling the second-named valve, a movable wall separating the two chambers of the pressure device, a second bellows, means connected with said second bellows for operating the first-named valve, and a third valve, operated by the said movable wall, for either connecting said second bellows with the first-named chamber of the pressure device or disconnecting it therefrom.

6. In an automatic player for musical instruments the combination of a wind chest, a pump connected with said wind chest and provided with a by-pass for allowing a portion of the air set in motion by the pump to circulate within the pump, a valve for closing said by-pass, an automatic pressure device having a chamber connected with said wind chest permanently, another chamber adapted for connection with the surrounding air, a valve controlling the connection of said second-named chamber with the surrounding air, a normally expanded bellows communicating permanently with the first-named chamber of the pressure device, means operated by said bellows for controlling the second-named valve, a movable wall separating the two chambers of the pressure device, a second bellows, means connected with said second bellows for operating the first-named valve, a third valve operated by said movable wall for either connecting said second bellows with the first-named chamber of the pressure device or disconnecting it therefrom, and means operated by the second bellows at the time it opens the first-named valve for causing said first bellows to close the second-named valve.

7. In an automatic player for musical instruments the combination of a wind chest, a pump connected with said wind chest and provided with a by-pass for allowing a portion of the air set in motion by the pump to circulate within the pump, a valve for closing said by-pass, an automatic pressure device having a chamber connected with said wind chest permanently, another chamber adapted for connection with the surrounding air and connected with the first-named chamber by a bleeding channel, a valve controlling the connection of said second-named

chamber with the surrounding air, means responsive to a change of pressure in the first-named chamber for operating the second-named valve, a movable wall separating 5 said two chambers, pneumatically operated means for moving the first-named valve, and a third valve operated by the movement of said wall for either connecting said pneumatically operated means with the first-named chamber of the pressure device or 10 disconnecting it therefrom.

8. In an automatic player for musical instruments the combination of a wind chest, a pump connected with said wind chest and 15 provided with a by-pass for allowing a portion of the air set in motion by the pump to circulate within the pump, a valve for closing said by-pass, an automatic pressure device having a chamber connected with said 20 wind chest permanently, another chamber adapted for connection with the surrounding air, a valve controlling the connection of said second-named chamber with the surrounding air, means responsive to a change 25 of pressure in the first-named chamber for operating the second-named valve, additional means under the control of the operator for admitting the surrounding air to said second-named chamber when desired, 30 a movable wall separating said two chambers, pneumatically-operated means for moving the first-named valve, and a third valve operated by the movement of said wall for

either connecting said pneumatically-operated means with the first-named chamber 35 of the pressure device or disconnecting it therefrom.

9. In an automatic player for musical instruments the combination of a wind chest, a pump connected with said wind chest and 40 provided with a by-pass for allowing a portion of the air set in motion by the pump to circulate within the pump, a valve for closing said by-pass, an automatic pressure device having a chamber connected with said wind chest permanently, another chamber 45 adapted for connection with the surrounding air, a valve controlling the connection of said second-named chamber with the surrounding air, means responsive to a change 50 of pressure in the first-named chamber for operating the second-named valve, a movable wall separating said two chambers, pneumatically-operated means for moving the first-named valve, and a third valve operated by the movement of said wall and having two connected members one of which 55 opens or closes the communication between said pneumatically-operated means and the first-named chamber of the pressure device 60 while the other member of said third valve closes or opens the communication between said pneumatically-operated means and the outside air.

TOLBERT F. CHEEK.
